UNITED STATES PATENT OFFICE.

LOUIS STEINBERGER, OF NEW YORK, N. Y.

INSULATING-FIXTURE.

No. 871,002.

Specification of Letters Patent.

Patented Nov. 12, 1907.

Application filed November 5, 1906. Serial No. 342,008.

To all whom it may concern:

Be it known that I, LOUIS STEINBERGER, a citizen of the United States, and a resident of the city of New York, borough of Brooklyn, in the county of 5 Kings and State of New York, have invented a new and Improved Insulating-Fixture, of which the following is a full, clear, and exact description.

My invention relates to an insulating fixture adapted for use in connection with arc lights; also as a suspension device in connection with span wires for supporting a trolley line wire, and is especially serviceable as an insulating support and strain member, and when desired, may be employed also as a turn buckle.

The device may be employed in a variety of ways 15 for insulating conductors; and is well adapted to act in combination with other fixtures.

Among the purposes accomplished by my invention are the following:

1. To provide an improved and efficient form of fastening whereby the insulating member and its accompanying parts may be readily attached to or removed from a wire or other support.
2. To provide an improved device capable of service both as a strain and as a turn-buckle.
3. To provide in the device just 25 mentioned, a built-up ring made in separate pieces connected together.
4. To improve the insulation of the wires or conductors as supported by the device.
5. To facilitate the dripping of moisture from the outside of the central casing employed.
6. To provide 30 various details of construction whereby the general efficiency of the device is improved.
7. To provide a device which may be securely retained in operative position by a plurality of guying attachments.
8. To provide an insulating device which admits of employing 35 various forms of attaching, suspending, straining or supporting parts.

Reference is to be had to the accompanying drawings forming a part of this specification, in which similar characters of reference indicate corresponding parts 40 in all the figures.

Figure 1 is a plan view of the insulating fixture complete, and showing the turn-buckle bolts 37 as well as the bifurcated eye-bolt 25; Fig. 2 is a central vertical section showing the disposition of the upper 45 and lower supporting bolts, the anchorages, and insulator therefor, the turn buckle bolts, and the insulated threaded sleeves between the same; Fig. 3 is an elevation of the parts assembled, with the exception of the general mass 39 of insulating material which is 50 afterward applied as in Fig. 2; Fig. 4 is a section on the line 4-4 of Fig. 3 looking in the direction of the arrow and showing how the two annular members 7

are secured together so as to hold certain other parts in position; Fig. 5 is a perspective of one of the annular members 7, showing the arrangement of the lugs 7* 55 and arches 9; and Fig. 6 is a side elevation of the lower bolt 16 and one of the electrose sleeves 13 provided with a neck 14 and an annular flange 15, for the purpose of thorough insulation.

The two annular members 7 are provided with lugs 60 7* projecting internally and with holes 8 and arches 9; the arches, like the holes are spaced equi-distant, the holes being alternated with the arches, as will be understood from Fig. 5. The annular members 7 are secured together by rivets 10 provided with heads 11. 65 Fitted intermediate of the annular members 7 and encircled by the arches 9 thereof, are sleeves 12, 13, provided with necks 14 and flanges 15, these sleeves, necks and flanges being of insulating material. One of these sleeves is molded upon the bolt 16 which is provided 70 with a head 17 having a slot 18 and bevel shoulders 19, for the purpose of holding the sleeve securely thereupon. The bolt 16 terminates at its lower end in a clevis 20 provided with a screw-bolt 21 extending therethrough. The upper sleeve 22 is provided with a neck 23, and 75 flanges 24, being substantially similar to the sleeve 13. The sleeves 12, 13 and 22 together with their respective flanges and necks are of insulating material, preferably electrose. The neck 23 and flange 24 encircle the lower end of the bolt 25, the upper end of this bolt being 80 provided with hooks 26, 27, flattened upon their adjoining surfaces and disposed oppositely to each other, these members standing apart so as to leave a slot 28, as may be seen from Fig. 1, and being so bent in vertical planes as to form a circular aperture 29, as will be seen in Fig. 85 2. The eye bolt 25 is therefore bifurcated.

The lower end of the eye-bolt 25 terminates in a head 31 somewhat similar to the head 17 above described, and provided with an aperture 30 extending entirely therethrough. This aperture is filled with insulating 90 material at the time when the sleeve 22 is cast upon the head 31 and lower end of eye-bolt 25. The pair of metal sleeves are threaded internally as shown, and are each provided with an enlarged portion 33 serving as an anchorage. These sleeves 32, including their enlarged 95 portions 33, are covered by sleeves 34 of insulating material, provided with flanges 35 and with necks as will be understood from the foregoing description of sleeves 13 and 22.

Eye-bolts 37 are provided with threaded portions 38 100 which are adapted to screw into and out of the sleeves 32. The pitch of the thread is arranged as indicated in Fig. 2, so that the two bolts 37 are either drawn inward or pushed outward as the case may be, simultaneously,

one being provided with a right-hand thread, the other with a left-hand thread.

The parts above described, being assembled as indicated in Fig. 3, a mass 39 of insulating material is now 5 pressed into and around the center of the skeleton, and is so shaped externally as to form annular hoods 40, 41, and petticoats 42, 43; the purpose of which is to facilitate the dripping of moisture, and to increase the insulation so as to take up surface leakage.

10 The device above described may be used in a number of different ways. For instance, if it be desired to merely support a single conductor, the prongs 26 are placed astride of the supporting wire or the like, and the device is given a quarter turn in a so-called "clock-wise" direction; this leaves the insulating fixture hanging from the support. The pin 21 is now withdrawn, the conductor moved up into the clevis, and the pin replaced. This leaves the conductor supported. Of course, the relative position of the clevis and divided 20 eye-bolt may be changed at will.

Where it is desired to use the device as a turn-buckle the bolts 16, 25, need not necessarily be brought into use; the two wires or cables to be tightened are connected with the eye-bolts 37 and the body portion 39 is 25 simply rotated so as to draw these bolts closer together and tighten the wires connected thereto.

The variety of uses to which this insulating fixture may be applied are so obvious that it is thought that further explanation is unnecessary.

30 I find it a good idea to make the sleeves 12, 13, 34, together with their necks and flanges, of comparatively tough insulating material, such as electrose, and for froming the body portion 39, a cheaper grade of insulating material may be employed.

35 It will be understood that when the two annular members 7 are placed together, that they constitute a ring-like member, the arches 9 being arranged in pairs, together forming annular eyes.

I do not limit myself to the exact form or construction 40 of any or all of the parts above described nor to the precise grouping of them as shown, neither do I limit myself to the employment of any particular insulating material; I prefer however, to use the insulating material known in the art as "electrose".

Having thus described my invention I claim as new, 45 and desire to secure by Letters Patent:—

1. An insulating fixture comprising a pair of annular metallic members provided with arches, and apertures, and further provided with lugs disposed adjacent to said apertures, for the purpose of strengthening said annular metallic members, rivets extending through said apertures and holding said annular members together, the arrangement of said annular members being such that the arches of one annular member mate the arches of the other annular member, thus forming eyes, bolts extending into 50 said eyes, and means for insulating said bolts from said annular members.

2. An insulating fixture comprising a pair of annular metallic members provided with arches, said annular metallic members being further provided with lugs extending internally thereof for the purpose of strengthening said annular metallic members, fastening members securing the lugs of one of said annular members to the lugs of the other annular member for the purpose of holding said annular members together, and eye-bolts extending through 55 said arches and insulated therefrom.

3. An insulating fixture comprising a pair of annular metallic members provided with arches and so disposed that said arches of one annular member mate the arches of the other annular member, said annular members being 70 provided with lugs disposed internally thereof and further provided with holes extending through said lugs, and fastening members extending through said lugs for the purpose of securing said annular members together, sleeves of insulating material mounted within said arches, and 75 metallic suspension members provided with portions connected with said sleeves of insulating material.

4. An insulating fixture comprising a ring made in halves, eye-bolts extending radially into said ring and disposed intermediate said halves, sleeves of insulating material extending through said eye-bolts, and metallic members extending into said sleeves and thus insulated from 80 said ring.

5. The combination of a divided ring made in halves, 85 said halves being provided with oppositely disposed arches and further provided with apertures, fastening members extending through said apertures for the purpose of connecting said halves together, sleeves of insulating material encircled by said arches and held in position thereby, and bolts provided with portions extending into said sleeves. 90

In testimony whereof I have signed my name to this specification in the presence of two subscribing witnesses.

LOUIS STEINBERGER.
